UNITED STATES PATENT OFFICE.

JOHN LAWRENCE MORGAN, OF EVERETT, MASSACHUSETTS, ASSIGNOR TO JOHN MANNING VAN HEUSEN, OF BOSTON, MASSACHUSETTS.

COLLAR.

1,254,340.

Specification of Letters Patent. Patented Jan. 22, 1918.

Application filed May 22, 1917. Serial No. 170,225.

To all whom it may concern:

Be it known that I, JOHN LAWRENCE MORGAN, a citizen of the United States, residing at #34 Evelyn road, Everett, in the county of 5 Middlesex, State of Massachusetts, have invented certain new and useful Improvements in Collars; and I do hereby declare the following to be a full, clear, and exact description of the invention, such as will enable 10 others skilled in the art to which it appertains to make and use the same.

This invention relates to improvements in folding collars, and more particularly to folding collars of multiply fabric woven in a single piece and provided with a weakened or 15 fold portion, the fabric being so woven that the outer portion of the collar will be longer than the inner portion.

The invention will be described more in 20 detail in connection with the accompanying drawings which illustrate, more or less diagrammatically, the collar and the collar fabric, and the method and apparatus for weaving the fabric. In the accompanying drawings—

Figure 1 is a diagrammatic representation of certain of the working parts of the loom suitable for the manufacture of the collar fabric.

Fig. 2 is a face view of the tapered tension rolls of Fig. 1.

Fig. 3 is a plan view of a piece of the fabric passing over the angular or skewed guide rod.

Fig. 4 is an enlarged diagrammatic cross section of the fabric on a line parallel to the warp thread, that is, a section lengthwise of the fabric.

Fig. 5 is a similar enlarged diagrammatic cross-section taken at right angles to that of Fig. 4, that is, a section taken parallel to the weft thread of the fabric.

Fig. 6 is a face view of the fabric having a portion broken away to expose certain of 45 the warp and weft threads.

Fig. 7 is a diagrammatic representation in perspective of a piece of the fabric.

Fig. 8 is a diagrammatic cross-section of a fabric provided with a modified fold portion.

Fig. 9 shows in perspective a collar embodying the invention.

Fig. 10 shows a portion of the fabric with the collar blank indicated thereon in dotted 55 lines.

Fig. 11 shows the collar blank from the fabric; and

Fig. 12 shows the blank bound and in its finished state ready to be folded.

In describing the invention more in detail 60 in connection with the accompanying drawings and with the embodiment or embodiments of the invention illustrated thereon, it will be understood that the drawings as well as the description are intended to be illustrative of the invention and that variations and modifications can be made in the embodiment illustrated and described without departing from the spirit and scope of the invention.

Referring more particularly to Figs. 1 to 70 3, wherein the production of the collar fabric is illustrated, it will be seen that the warp and binder threads are carried in rolls 1—1 and from there pass over the guide rods 2 and then through the spacing frame 3 and around the guide rods 4 and through the frames 6—6. Each warp and binder thread, after passing through the thread supporting loop of the frame 6, passes through the reed 80 7 supported on the beam 8 and operating in a manner which will be readily understood. The cloth is completely formed at the point 9 and thence passes over the skewed or angular guide rod 10 and between the tapered tension rolls 11 and 12 to the take-up roll 13.

The tapered tension rolls are shown in Fig. 2 and are of such proportions that the fabric produced will have a predetermined greater length on one side than on the other. 90 This lengthening of the fabric on one side, as compared to the other, is accomplished by the tapered rolls, by pulling and thereby feeding the warp threads through the frames in proportion to the circumference of the tapered rolls at the point where a given warp thread passes over the rolls in the fabric. It will thus be noted that while the tension rolls operate on the completed cloth, the effect of the operation is upon the warp 100 threads before the weft threads have been put in to form the fabric, and hence this action is upon the fabric at the time of its formation.

The fabric thus produced and utilized in 105 the manufacture of the novel collar of the present invention is a multiply fabric; and the particular fabric illustrated is a two-ply fabric. This two-ply fabric consists of an upper and a lower fabric of the ordinary 110

weave and a middle portion composed of filling or gut threads, the upper and lower fabric with the gut threads between them being held together with binder threads.

5 The construction of the fabric, according to the preferred embodiment of the invention, is illustrated somewhat diagrammatically in Figs. 4 to 7 inclusive.

Referring first to Fig. 4, it will be seen 10 that the weft threads 17-17 of the upper and lower fabrics or plies are woven with the warp threads 18-18, while the filling or gut threads 20 lie lengthwise between the upper and lower fabrics and are held in 15 place by the binder threads 21.

The section of Fig. 5 is taken at right angles to that of Fig. 4 and shows the warp threads 17-17 of the upper and lower fabrics woven with the weft threads 18-18, 20 and the filling threads 20 between the two outer plies or fabrics. At the point indicated by the numeral 23, certain of the filling or gut threads 20 are omitted, thereby producing a weakened or fold portion in the 25 fabric extending lengthwise of the fabric. In the particular structure shown in Fig. 5, eight of these longitudinal filling threads are omitted. The production of the weakened portion in this way does not affect the 30 upper and lower layers or plies of the fabric which still present an uninterrupted and finished appearance.

In Fig. 6 the fabric is shown with portions 35 broken away to expose the warp threads 20 and to show the space 23 where the filling threads have been omitted to form the weakened or fold portion. This weakened or fold portion is further indicated at 25 in Fig. 7 as a well defined line or space along which 40 the folding of the collar takes place.

In Fig. 8 the fabric is provided with a modified form of weakened or fold portion. This fabric, which is also a two-ply fabric, is composed of an upper fabric woven from 45 warp threads 29 and weft threads 30 and a lower fabric woven from warp threads 31 and weft threads 32. Between the upper and lower fabrics or plies are the filling or gut threads 33. The fold portion of the fabric is 50 made by omitting the threads 33 and combining the upper and lower fabrics into a single fabric having double the number of warp and weft threads. The fabric is thus made very dense and firm at the fold portion 55 so that it has greater wearing qualities.

The fabric may be produced of different widths and with variations in its constructions and proportions, as will be readily understood. The fabric may, for example, 60 have a width of about five and one-half inches, and be divided by the weakened or fold portion 14 into a panel 15 about three inches wide and a panel or portion 16 slightly less than two and one-half inches 65 wide, as indicated in Fig. 3.

It will also be evident that the panel 15 can be made of a predetermined greater length than the panel 16, this regulation being effected by the contour or taper of the tension rolls. The fabric may, for example, 70 be about 16½% longer at the outer edge of the longer panel than at the inner edge of the shorter panel. For example, if the right hand warp thread of the fabric illustrated in Fig. 2 travels at the rate of 36 inches in a given period of time, the left hand warp 75 thread may travel about 42½ inches in the same time interval; while any intermediate warp thread will travel a proportional distance, according to its position in the fabric. 80

The fabric may, for example, be produced having 352 warp threads to the inch and 200 weft threads to the inch, in which case there would be 88 warp threads in each of the upper and lower fabrics, 88 filling or gut 85 threads and 88 binder threads binding the upper and lower fabric together and holding the filling threads firmly in place. The binder threads are evenly distributed over the surface of the fabric, particular attention being paid to having a binder thread 90 come at each end of the space 23 (where certain of the warp threads are omitted in order to produce the weakened or fold portion.)

In producing the collar from the finished fabric, the collar blank 26 may be stamped from the fabric as indicated in Fig. 10, and the blank thus produced, as shown in Fig. 11 may be then provided with a binding 28 to finish the edge of the collar. After addition of button holes the finished collar will 100 be produced. This collar, before folding, will be flat as indicated in Fig. 12. The folding of the collar will take place along the weakened or fold portion produced in 105 the fabric as above described.

It will be noted that the fabric as a whole has a "twist" in it and that the outer panel is woven longer than the inner panel. The fabric will thus partake of a curvilinear 110 shape and the weakened or fold portion will likewise be curvilinear. The collar made from the fabric will similarly have a curvilinear fold portion as clearly indicated at 24 in Figs. 10 to 12. When the flat collar with this curvilinear set is folded, as indicated in Fig. 9, it will naturally assume a permanent curvilinear shape or set and will 115 fold smoothly along the fold or weakened portion. Moreover, since the outer panel or folding portion of the collar is longer than the inner portion, the tendency of the outer portion to bind upon the inner portion will be avoided. By giving to the outer portion the proper increase in length, as compared to the inner portion, ample space can be 120 provided to permit a necktie to pass freely between the inner neck-band portion of the collar and the outer turn-down portion.

Where the fabric as a whole is woven un- 130

der the same tension, and where the outer turn-down portion is woven of a greater length than the inner portion, the collar will retain its form and its permanent curvilinear set after laundrying. Moreover, by constructing the collar of fabric produced in the manner described, the collar will be flat when unfolded, and can be readily laundryed without added precautions, while the 10 collar will nevertheless assume the desired curvilinear shape when again folded.

It will be further noted that there are the same number of weft threads on each side of the weakened or fold portion, even 15 though the fabric is longer on one side of this fold than on the other. It follows that there will be a greater number of weft threads per inch in the inner or neck-band portion of the collar than in the outer or 20 turn-down portion. So also, since the warp threads are drawn or fed faster in the longer portion of the fabric, there will be a greater length of the warp threads in the longer or outer portion of the fabric or 25 collar than in a corresponding portion of the inner or neck-band portion of the fabric or collar.

The different layers or plies of the fabric may be made of different material and this 30 may, in particular, be desirable where a finer or more expensive material is desired in the outer ply than is necessary in the other plies of the fabric.

It will thus be understood that the collars 35 may be made of different materials, or different combinations of materials; and also that the fabrics may be woven of different degrees of fineness. So also, the collars may be made of various shapes and proportions, 40 as will be readily understood.

I claim:

1. A folding collar, made up of an inner panel and an outer panel of two-ply fabric woven in one piece under the same tension 45 and having an intermediate edge-fold portion, the outer panel being longer than the inner so that the collar will take on a curvilinear set when folded; substantially as described.
2. A folding collar, made up of an inner panel and an outer panel of two-ply fabric woven in one piece under the same tension 50 and having an intermediate edge-fold por-

tion, the outer panel being longer than the inner so that the collar will take on a curvilinear set when folded; substantially as described. 55

3. A folding collar, made up of an inner panel and an outer panel of two-ply fabric woven in one piece under the same tension 60 and having an intermediate weakened edge-fold portion, the outer panel being longer than the inner so that the collar will take on a curvilinear set when folded; substantially as described. 65

4. A folding collar, made up of an inner panel and an outer panel of two-ply fabric woven in one piece under the same tension 70 and having an intermediate weakened edge-fold portion, the outer panel being longer than the inner so that the collar will take on a curvilinear set when folded; substantially as described.

5. A folding collar made up of an inner panel and an outer panel of two-ply interwoven fabric woven in one piece and having an intermediate edge-fold portion, the outer panel being woven with an inherent curvilinear set; substantially as described. 75

6. A folding collar made up of an inner panel and an outer panel of two-ply interwoven fabric woven in one piece and having an intermediate edge-fold portion, both the inner and outer panels being woven 85 with an inherent curvilinear set; substantially as described. 80

7. A folding collar, made up an inner panel and an outer panel of two-ply fabric woven in one piece and having an intermediate edge-fold portion, the outer panel being woven longer than the inner and being longer at its outer edge than at its inner edge; substantially as described. 90

8. A folding collar, made up of an inner panel and an outer panel of two-ply fabric woven in one piece and having an intermediate edge-fold portion, the fabric being woven progressively longer from the inner edge of the free inner panel to the free outer 100 edge of the outer panel; substantially as described.

In testimony whereof I affix my signature.

JOHN LAWRENCE MORGAN.
